COMBINATION LOCK

Katharina Lechner, Vienna, Germany

Application November 1, 1938, Serial No. 238,130
In Austria November 3, 1937

4 Claims. (Cl. 70—299)

This invention relates to a combination lock with control pieces including elements which are provided with two superposed stepped portions and which are actuated by outer keys designated for instance by numerals and used to move the control pieces in the axial direction.

In prior art, such control pieces had the form of crosses extending in two layers, which were slidably arranged between three plates, the two outer plates of which were immovable and provided with openings having the form of the profile of the control pieces, while the middle plate which carried the crossbar of the lock or which was integral with the crossbar was rotatable between the two fixed plates. This middle plate was provided with elongated slots or transverse openings corresponding in form to certain parts of the control pieces, so that the lock could be opened after the withdrawal of further movement of the control pieces. The control pieces were so arranged that in their displaced position their longitudinal arms extend into the elongated slots.

Locks of this type have the disadvantage that the control pieces may move in relation to the plates as a result of even small shocks, with the result that the locking device may open or become inoperative. An object of the present invention is to eliminate this drawback by providing means for securing the control pieces against unintended movements, for instance, by arranging the control pieces upon slotted bolts having the form of split pins.

Another drawback of locks known in prior art is the necessity of using elements consisting of two layers and having the form of double crosses. The cost of manufacturing these double crosses is very high, particularly as far as locks of small dimensions are concerned, and these crosses break easily irrespective of the material of which they are made. Furthermore, if the slots and openings of the plates are not quite exact, the crosses may become jammed or may damage the sharp edges of the slots. The manufacture of such crosses requires special skill, with the result that manufacturing costs are further increased.

Another object of the present invention is to eliminate these drawbacks through the use of control pieces having T-shaped heads or heads of a half-cross form.

In accordance with the present invention, the cost of production may be further decreased by substituting circular plates having cylindrical portions of different diameters arranged in a stepped formation for the aforesaid crosses, al-

though in that case the central step must be made as small as possible.

The drawing illustrates by way of example two forms of a lock constructed in accordance with the principles of the present invention.

In the drawing:

Figure 1 is a top view of a round lock wherein half crosses are used as control pieces, the cover and the upper carrying plate being partly broken off;

Figure 2 is a top view of a round lock wherein round or circular plates are used as control pieces, the cover and the upper carrying plate being partly broken off;

Figure 3 is a cross-section through the lock shown in Figure 1 on a somewhat larger scale;

Figure 4 is a perspective view of a control piece used in the device shown in Figures 1 and 3; and

Figure 5 is a perspective view of a control piece used in the device shown in Figure 2.

Each of the two locking devices illustrated in the drawing comprises three superposed plates *a*, *b*, and *c* which are situated within a casing *d*. The two outer plates *a* and *c* are firmly connected with the casing and are therefore immovable, while the middle plate *b* is rotatable about its central axis. The middle plate *b* has a square central opening into which a square portion of a pin *f* is fitted, so that the plate *b* is rotated along with the pin *f*.

Obviously, the pin *f* may be made immovable and the plate *b* may be caused to rotate around the pin *f*.

A hook *e* also has a square opening into which a square portion of the pin *f* is fitted, so that the hook *e* rotates along with the plate *b* and the pin *f*. Obviously, the hook *e* may constitute a part of the plate *b*.

A number of control pieces *g* are arranged in a circle around the central axis of the plates.

The control pieces shown in Figures 1, 3, and 4 comprise an upper larger head portion *g*₁ and a smaller lower head portion *g*₂ which have the form of a T or a half cross.

Each of the control pieces is provided with a slotted bolt *n* having the form of a split pin.

The plates *a*, *b*, and *c* have openings the form of which corresponds to that of the control pieces. The upper plate *a* and the lowest plate *c* have openings *h*₁ corresponding to the larger head portion *g*₁ of the control pieces *g* while the middle rotary plate *b* has openings *h*₂ which are integral with elongated slots *h*₃ into which the portions *g*₂ of the control pieces may be fitted.

The control pieces are actuated by means of

keys *i* which are depressed manually and which are returned into their original position by means of springs. The keys *i* are arranged in a circle and may be designated by numerals or other insignia.

5 The device used for returning the displaced control pieces to their original position comprises a returning plate *k*, which may be raised by means of a flange *l* constituting a part of the pin *f*,

10 which is provided with a handle *m* so that it can be easily grasped and pulled in the axial direction. Furthermore, the same handle *m* may be turned to rotate the middle plate *b*, which is rotatable along with the pin *f*.

15 Due to the provision of the slotted bolts *n*, the control pieces are held in their proper position by the spring action of these bolts, so that it is possible to move them relatively to the plates only by a comparatively strong pressure or action.

20 The device is operated as follows:

The control pieces are originally set in the upper plate *a* in such manner that most of them have their larger upper portions *g*₁ situated in the openings *h*₁ of the upper fixed plate *a*, while 25 their smaller head portions *g*₂ are situated in the openings *h*₂ of the movable plate *b*. If all the control pieces were located in this position, the middle plate *b* could be rotated relatively to the plates *a* and *c*. However, some of the control 30 pieces are arranged in such manner that their smaller head pieces *g*₂ are situated in the openings *h*₁ of the upper plate *a*, while their larger head portions *g*₁ are situated in the openings *h*₂ of the middle plate *b*. Then it is not possible to 35 move the middle plate *b* any more, since the last-mentioned control pieces lock this plate against movement.

For example, the positions of three control pieces actuated by keys *i* numbered 2, 1, and 3, 40 may be arranged in reverse positions in this manner.

In order to open the lock, it is necessary to move these three reversed control pieces in such manner that they will not lock the middle plate *b* 45 any more. This can be achieved by moving the smaller head portions *g*₂ of the three reversed control pieces into the openings *h*₂ of the middle plate *b* and by moving the larger head portions *g*₁ of these pieces into the openings *h*₁ of the lower-most plate *c*. In order to move the reversed con-

5 trol pieces to these positions, it is necessary to depress the keys numbered 2, 1, and 3 until the reversed control pieces are moved inwardly to the extent of the thickness of a plate.

If the operator by mistake depresses the wrong 5 control piece, so that one of the three reversed control pieces is not moved into the correct position, the lock remains locked and does not open even if later on he operates the correct key.

In order to open the lock, it is necessary first to 10 reset all the keys and control pieces by raising the returning plate *k* and then to press the correctly numbered keys, whereupon the middle plate can be turned to unhook the hook *e*.

The described lock can be used not only for 15 locking doors of all kinds but also for motorcars, as a lock for the starting device, the car door, the ignition, and the like.

What is claimed is:

1. In a combination lock consisting of stepped 20 control pieces in two layers displaceable by means of keys marked on their outer face between and vertically to carrying plates, in which the said control pieces are held by the spring action of split pin-like slotted bolts in their proper position.

2. In a combination lock consisting of stepped control pieces in two layers displaceable by means of keys marked on their outer face between and vertically to carrying plates, in which the said 30 control pieces are of a T-head form.

3. In a combination lock consisting of stepped control pieces in two layers displaceable by means of keys marked on their outer face between and vertically to carrying plates, in which the said 35 control pieces consist of circular plates with a central boltlike nose.

4. In a combination lock, in combination, three superposed plates, movable control pieces extending perpendicularly to said plates, each of said control pieces having two portions adapted to engage openings formed in two of said three plates, one of said three plates being rotatable relatively to the other two plates, each of said control pieces also having mechanical locking means 45 maintaining it in position relatively to said plates to prevent the shifting of the control piece; and separate keys for actuating said control pieces.
